(57) **CLAIM**

The ornamental design for a coffee cup lid as shown and described.

DESCRIPTION

FIG. 1 illustrates a perspective view illustrating the overall shape of a coffee cup lid, showing my new design;

FIG. 2 illustrates a front view of the design;

FIG. 3 illustrates a rear view of the design;

FIG. 4 illustrates a left view of the design;

FIG. 5 illustrates a right view of the design;

FIG. 6 illustrates a top view of the design;

FIG. 7 illustrates a bottom view of the design;

FIG. 8 illustrates a perspective view illustrating the overall shape of the design as seen from the back;

FIG. 9 illustrates a perspective view illustrating the overall shape of the design as seen from the bottom;

FIG. 10 illustrates a cross-sectional view taken along line A-A' in FIG. 7; and,

FIG. 11 illustrates a reference cross-sectional view explaining the inflow of coffee concentrate, etc., in use.

This design product has a whirlpool-shaped guide on the inner side, and even when combined with a cup, beverages such as coffee concentrate or milk can be slowly added through the whirlpool-shaped guide.

In this design product, as shown in FIG. 11, the coffee liquid flows in through the inlet provided on the side of the straw hole, slowly flows down along the whirlwind guide, and is discharged through the outlet.

This design product has a transparent outer surface so that the state of the inflowing coffee solution or milk can be checked. The material is synthetic resin.
